JOHANN FRIEDRICH MAX PATITZ, OF MILWAUKEE, WISCONSIN, ASSIGNOR TO ALLIS-CHALMERS COMPANY, OF MILWAUKEE, WISCONSIN, A CORPORATION OF NEW JERSEY.

TURBINE-WHEEL.

No. 867,407.

Specification of Letters Patent.

Patented Oct. 1, 1907.

Application filed October 19, 1903, Serial No. 177,663. Renewed March 24, 1905. Serial No. 261,736.

To all whom it may concern:

Be it known that I, JOHANN FRIEDRICH MAX PATITZ, a citizen of the United States, residing at Milwaukee, in the county of Milwaukee and State of Wisconsin, have invented a new and useful Turbine-Wheel, of which the following is a specification.

My invention relates to steam turbine wheels.

The object of the invention is to produce a wheel which shall possess great strength combined with minimum weight, which is easily assembled, whose vanes are so arranged that they can be readily inserted and rigidly attached, and whose steam passages are of the proper shape to give the best efficiency.

Other objects of the invention will appear from the following description taken in connection with the accompanying drawing, forming part of the specification, in which:

Figure 1 is a face view of the wheel, part of the rim being broken away to show the vanes. Fig. 2 is a cross-section on the line $z-z$ of Fig. 1. Fig. 3 is a perspective view of one of the vanes. Fig. 4 is an enlarged cross-section on the line $y-y$ of Fig. 3.

Referring to the drawing, the wheel proper consists of the cast hub 1 and the steel side plates 2 and 3, which are united to this hub by rivets. These side plates are let into the projecting flange of the hub so that they are flush with its outer surface, thus presenting a smooth unbroken surface for both faces of the wheel. The vanes 4 are held between the two side plates. The plate 3 has large openings 5, which permit the steam, after having passed radially towards the center through the vanes, to freely pass to the next wheel chamber on the left of Fig. 2. Smaller openings 6, are provided in the plate 2, in order to allow steam to pass to the right hand side of the wheel also, so as to insure balance of pressure on both sides of the wheel. The vane 4 is formed in one piece with its fastening rivets 4^a 4^b , and may be either drop-forged or cast. The front and rear faces of the vanes 4^a , 4^b , are given the proper outline for the passage of the steam.

End flanges 4^d 4^e are provided, carrying the integral rivets 4^a 4^b . These flanges are beveled outwardly as to steam flow in order to provide a passage for the steam which is flaring or gradually increasing in cross-section towards the center of the wheel. The purpose of this construction is to provide a free passage for the steam. The cross-section in an axial direction of the entering jet is determined by the space between the thicker portions of the flanges 4^d . As the steam flows from the circumference towards the center of the wheel, the transverse distance across the passage gradually diminishes because of the diminishing radius. In order, therefore, to permit the jet to pass out between the

vanes freely and without interference with the next following jet, or the formation of whirls, the passage is increased axial and made flaring, as shown, thus allowing the jet to expand axially.

Having thus described my invention, what I claim is:

1. A turbine-vane provided with flanges at the vane ends extending beyond the concave side of the vane, said flanges being beveled outwardly as to steam flow, and being provided with fastening means for the vanes, substantially as described. 60
2. A turbine vane, flanges at the vane ends extending beyond the concave side of the vane, and pins on the flanges for fastening the vane. 65
3. A turbine vane provided with flanges at the vane ends extending beyond the concave side of the vane, said flanges being beveled outwardly as to steam flow and fastening means on the flanges for holding the vane. 70
4. A turbine wheel consisting of a hub and two side plates and vanes inserted between the plates and fastened thereto, said vanes consisting of a central curved part, end flanges extending to the outer lines of the curved part, beveled portions on the flanges affording increasing cross section of steam passage, and fastening means on the flanges and co-acting with the side plates of the wheel. 75
5. A turbine wheel comprising a hub, side plates attached to said hub, and flanged vanes rigidly held between the side plates the flanges being formed to provide nozzle passages between the vanes. 80
6. A wheel including annular side plates, a hub upon which the plates are mounted, and vanes peripherally mounted between the side plates, the plates being ported for exhaust and for balancing. 85
7. The combination with a turbine shaft, of a turbine running wheel having an interior cavity and apertures in both side walls communicating with the exterior at the sides of said wheel and between the shaft and the periphery of the wheel; said wheel being provided with peripheral vanes arranged for the inward delivery of motive fluid to said cavity, and the interior wall-faces of said cavity being substantially parallel. 90

8. The combination with a turbine shaft, of a turbine running wheel having an interior cavity and apertures in both side walls communicating with the exterior at the sides of said wheel and between the shaft and the periphery of the wheel; said wheel being provided with peripheral vanes arranged for the inward delivery of motive fluid to said cavity, and the interior wall-faces of said cavity being substantially parallel adjacent to the vanes. 95

9. The combination with a turbine shaft, of a turbine running wheel comprising parallel side disks; vanes interposed between the peripheral portions of said disks; and nozzles arranged for the inward delivery of motive fluid to the vanes and the interior space between said disks; said disks being both provided with apertures, of greater capacity than the capacity of the nozzles. 100

In testimony whereof I have signed my name to this specification in the presence of two subscribing witnesses.

JOHANN FRIEDRICH MAX PATITZ.
